D. L. POWERS

SPRING LUBRICATOR

Filed Dec. 18, 1922

UNITED STATES PATENT OFFICE.

DANIEL L. POWERS, OF ARVADA, COLORADO.

SPRING LUBRICATOR.

Application filed December 18, 1922. Serial No. 607,534.

To all whom it may concern:

Be it known that I, DANIEL L. POWERS, a citizen of the United States, residing at Arvada, the county of Jefferson and State of Colorado, have invented certain new and useful Improvements in Spring Lubricators; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to a device adapted to be attached to an ordinary spring for the purpose of facilitating the proper lubrication thereof.

20 Springs, such as are ordinarily employed for supporting the bodies of vehicles, more especially those employed in connection with automobiles, are, almost without exception, formed from a plurality of leaves which are assembled so as to form a spring 25 of sufficient strength. The proper functioning of a spring of the multiple leaf type requires that the leaves shall be free to slide on one another, as only by so doing can the maximum amount of resiliency be obtained.

30 The springs of an automobile are, as a rule, exposed to the effect of rain from above and also to the splashings of mud and water from below, with the result that water finds its way between the leaves of the springs and 35 tends to make the adjacent surfaces rusty. When the springs rust, in the manner suggested, the leaves will no longer slide as required and the spring functions like a solid bar and not as a laminated structure.

40 It is usually difficult to lubricate a multiple leaf spring and they are therefore as a rule left unlubricated.

45 It is the object of this invention to provide a simple and inexpensive device that can be readily attached to any multiple leaf spring and which shall be so constructed and designed that it will permit oil to be constantly held against the side of the springs so that it may penetrate, by the help of capillary action, to the spaces between the adjacent surfaces and keep them properly lubricated.

In order to more clearly describe my invention, I shall have reference to the accompanying drawing, in which—

55 Fig. 1 is a side elevation of a portion of a laminated spring and shows my improved lubricator in place thereon.

Fig. 2 is a section taken on line 2—2, Fig. 1.

60 Fig. 3 is a view looking in the direction of the arrow 3 on Fig. 4.

Fig. 4 is a side elevation of my lubricator looking in the direction of the arrow 4, Fig. 3.

65 Fig. 5 is a view looking in the direction of the arrow 5 in Fig. 4 and shows the lubricator, partially disassembled; and

Fig. 6 is a section taken on line 6—6, Fig. 5.

70 The same reference numbers will be used to designate the same parts throughout the several views.

75 Numeral 1 designates, as a whole, a multiple leaf spring of ordinary construction, and 2 designates the various leaves of which the spring is composed. My improved lubricator, which I have designated as a whole by numeral 3, consists of two similarly constructed complementary members 4 and 5, 80 each of which is provided at one end with two upwardly projecting, perforated ears 6, one of which is threaded for the reception of the threaded end 7 of the bolt 8. The part 4 has downwardly projecting flanges 9 along the sides thereof and these form a channel within which the part 5 slides in a manner clearly apparent from the drawings. The parts 4 and 5 have downwardly extending end flanges 10 whose inner edges are 85 curved somewhat in the manner indicated by numeral 11 so that as the bolt 8 is rotated, the lubricator will be firmly clamped to the top leaf of the spring. Extending 90 downwardly from the ends 10 are semi-cylindrical extensions 12 whose lower ends are closed, as indicated by numeral 13. The cylindrical extensions 12 are filled with an absorbent material 14 which contacts the 95 edges of the leaves of the spring in the manner apparent from an inspection of Figs. 2 and 5. Holes 15 are provided in members 4 and 5 in the manner shown in Figs. 2 and 3.

My improved lubricator is clamped onto the spring in the manner apparent from the above description and from the drawing. Oil is then introduced through holes 15 in sufficient quantity to saturate the absorbent material 14. As the spring functions, oil will pass from the wicks 14 into the spaces between the leaves and keep the surfaces thereof properly lubricated.

From the above it will appear that I have invented a spring lubricator that can be cheaply made and readily applied to the springs and which has a large capacity for oil and which will automatically supply the needed lubrication to the spring.

Having now described my invention, what I claim is:

1. A spring lubricator comprising, in combination, two relatively movable members, each having two portions angularly related to each other, one of said portions being concave and adapted to fit against the side of a multiple leaf spring, the other portion of one of said members being flat and adapted to fit against the top of a spring, the corresponding portion of the other member being channel shaped and adapted to receive the flat portion of the other member

in adjustable relation, upwardly extending ears at the corners of each member and a 30 clamping bolt passing through said ears, and adapted to perform both the clamping and adjusting functions.

2. A spring lubricator comprising, in combination, two relatively movable members, each having a side portion and a top portion, said portions forming substantially a right angle with each other, the side portions being concave and adapted to receive and hold a piece of absorbent felt against 40 the sides of a multiple leaf spring, the top portions of one of said members being flat and adapted to rest on the uppermost leaf of a multiple leaf spring, the top portion of the other member being channel shaped and 45 adapted to receive the flat portion of the opposing member in adjustable relation, perforated ears extending upwardly above the top portions of each member and an adjusting bolt projecting through said ears 50 and adapted to clamp the members against the sides of a spring, the bolt thus performing both the clamping and adjusting functions.

In testimony whereof I affix my signature.
DANIEL L. POWERS
